UNITED STATES PATENT OFFICE.

WILLIAM L. BURNER, OF KOPPEL, PENNSYLVANIA, AND OSCAR E. KANTENWEIN, OF OAK PARK, ILLINOIS, ASSIGNEES TO KOPPEL INDUSTRIAL CAR AND EQUIPMENT COMPANY, OF PITTSBURGH, PENNSYLVANIA, A CORPORATION OF PENNSYLVANIA.

SUPPORTING MECHANISM FOR DUMP CARS.

Application filed October 29, 1925. Serial No. 65,564.

This invention relates to railway dump cars of the type in which the body is tiltably mounted, and has for an object the provision of novel means for supporting such body in its normal righted position and for insuring the easy removal of said means from its supporting position when it is desired to tilt the body.

Another object of the invention is to provide a support for the tilting body of a dump car which, when in supporting position or when being moved into or out of such position, will present a flat bearing surface which will be substantially parallel with a bearing surface on the car body with which it cooperates.

A further object of the invention is to provide a support for the tilting body of a dump car, which support is provided with a hinged portion adapted to engage the car body and be adjusted thereby so that the bearing surfaces of the hinged portion and the car body will be substantially parallel with each other.

These and other objects will be apparent from the following description and appended claims.

Referring to the drawings in which like reference characters refer to like parts, Fig. 1 is a cross sectional view of a portion of a dump car embodying the invention, the body in this view being shown in its normal righted and locked position; Fig. 2 is a similar cross sectional view showing the body tilted to one side; Fig. 3 is a side elevational view of the support; Fig. 4 is an end elevational view of the support, a portion of the bolster being shown in section, and Fig. 5 is a modification of the invention.

Referring now in detail to the drawings the reference character 1 indicates the underframe of a dump car, and 2 the body which is tiltably mounted on the underframe through the medium of suitable hinges 3. The underframe and body may be of any suitable construction and the body may be tilted and righted by any suitable mechanism.

In the present embodiment of the invention the body is so mounted on the underframe that it may be tilted to one side or the other to discharge the lading carried thereby. At each side of the car and adjacent each end thereof a support 4 is provided, the

lower end of which is pivotally connected with the underframe through the medium of a pin 5, while the upper end thereof is adapted to cooperate with the car body to support it or to permit it to be tilted. In the present embodiment of the invention the body of the car is provided with a member 6 having a downwardly depending portion 7 with which the support 4 is adapted to cooperate to support the body. Each of the supports 4 comprises a lower portion 8 which is pivotally connected with the underframe, and also comprises an upper portion 9 which is hinged to the portion 8 through the medium of a pin 10 which passes through both of these portions. This upper portion 9 is provided with a top surface 11 which is preferably flat and adapted to cooperate with a flat surface 12 formed on the portion 7 of the member 6. The supports 4 may be operated by means of the mechanism described and claimed in our pending application for Letters Patent, filed Aug. 21, 1925, Serial No. 51,582, for Dump car, or by means of any other suitable mechanism.

It will here be noted that the surface 12 slopes downwardly and outwardly, and that as the support 4 is moved into or out of engagement therewith the portion 9 will be automatically adjusted so that the surfaces 11 and 12 will be substantially parallel with each other, thus reducing the friction between these surfaces as well as providing a flat bearing surface for the car body when it is in its righted position, or when it is being moved into or out of its supporting position.

In Fig. 5 of the drawings a modification of the invention has been illustrated in which the portion 7 of the member 6 is provided with a hinged portion 9 having a flat surface 12 and the support 4 is a single member having a flat surface 11.

It will be apparent to those skilled in the art to which this invention appertains that changes may be made in the details and arrangement of the several parts forming this invention without departing from the spirit and scope of the appended claims.

Having thus described the invention what we claim as new and desire to secure by Letters Patent is:—

1. In a dump car, an underframe, a body

tiltably mounted on said underframe, a member pivotally mounted on said underframe for supporting said body in its righted position, and an adjustable bearing member interposed between said body and supporting member.

2. In a dump car, an underframe, a body tiltably mounted on said underframe, a member mounted on said underframe and movable into and out of supporting position with said body, and a hinged bearing member interposed between said body and support.

3. In a dump car, an underframe, a body tiltably mounted on said underframe, a member pivotally mounted on said underframe adapted to support said body in its normal righted position, said member embodying means whereby the engaging bear-

ing surfaces between said body and support are maintained substantially parallel.

4. A support for the tilting body of a dump car comprising a part pivotally mounted independent of said body, and a part loosely mounted on the first mentioned part adapted to adjustably engage said body.

5. In a dump car, an underframe, a body tiltably mounted on said underframe, and a support for said body movable into and out of supporting position with said body, said support comprising a hinged bearing member adapted to adjustably engage with said body.

In testimony whereof, we affix our signatures.

WILLIAM L. BURNER.
OSCAR E. KANTENWEIN.
